UNITED STATES PATENT OFFICE.

JOHN B. FLINT, OF CHELSEA, AND ARTHUR J. HOWARD, OF MALDEN,
MASSACHUSETTS; SAID FLINT ASSIGNOR TO ORLANDO E. LEWIS,
OF WINTHROP, MASSACHUSETTS.

DESIGN FOR A NAIL.

SPECIFICATION forming part of Design No. 25,211, dated March 3, 1896.

Application filed January 16, 1896. Serial No. 575,786. Term of patent 14 years.

To all whom it may concern:

Be it known that we, JOHN B. FLINT, of Chelsea, in the county of Suffolk, and ARTHUR J. HOWARD, of Malden, county of Middlesex, State of Massachusetts, have invented and produced a certain new and useful Design for a Nail, of which the following is a specification, reference being had to the accompanying drawings, forming a part thereof.

10 Figure 1 of the drawings is a perspective view of a nail, illustrating our design, and Fig. 2 is an edge view thereof.

The leading feature of our design consists in a nail having flat opposite sides and an offset head, one of the longitudinal edges of the nail having transverse grooves or depressions therein.

In the drawings the nail has flat opposite sides $a a'$ and an offset head b extended rearwardly from its longer longitudinal edge a^2 , 20 which edge has a series of transverse grooves or depressions a^3 therein, the front and rear edges converging toward the point of the nail.

We claim—

The design for a nail, substantially as set 25 forth.

In testimony whereof we have signed our names to this specification in the presence of two subscribing witnesses.

JOHN B. FLINT.

ARTHUR J. HOWARD.

Witnesses:

GEO. W. GREGORY,

EMMA J. BENNETT.
